LIFT TRUCK

George Quayle, Philadelphia, Pa., assignor to The
Yale & Towne Manufacturing Company, Stamford,
Conn., a corporation of Connecticut

Application November 4, 1939, Serial No. 302,897

8 Claims.

(Cl. 254—2)

This invention relates to a lifting truck of the type in which an elevating platform is lifted by an appropriate lifting mechanism. More particularly, this invention relates to a lifting truck of the type disclosed in the U. S. Stuebing Patent No. 1,785,368, owned by The Yale & Towne Manufacturing Company, the owner of this application.

Even more particularly, this invention relates to a lifting truck of the type in which the lifting platform is adapted to enter between the upper and lower floors of a reversible skid platform or pallet, with the feature that when the platform is elevated, the pallet is lifted off the ground or floor on which it rests.

The truck which I have conceived and reduced to practice utilizes an elevating platform which, preferably, forms a unit separate from the lifting head through which the platform is lifted. There are means whereby the platform is adapted for lifting movement relatively to the lifting head while maintained in assembled relation to that lifting head. Since the lifting head is at the front end of the truck, the said means holding the elevating platform in assembled relation to the lifting head are at the front end of the elevating platform, and I extend means from the said front end connecting means to the rear of the truck for operating means at the rear end of the platform whereby to simultaneously lift the front and rear ends of the platform.

More particularly, in my invention I employ a lifting head, which may be of any particular form having lifting mechanism, but which is preferably the type shown in the Stuebing patent supra. I provide an elevating platform pivoted, preferably through links, to the lifting head, with the feature that the platform is movable by the lifting means relatively to the lifting head. Naturally, the lifting means may be means acting to separate the lifting platform and lifting head, and thereby lifting the platform.

Through the provision of linkage means which are actuated when the front end of the platform is lifted relatively to the lifting head, wheels at the rear of the platform are simultaneously moved relatively to the platform and serve to lift the platform. Preferably, these rear wheels are so mounted that they are capable of moving between the boards of a reversible pallet, somewhat in the manner disclosed in my application for patent Serial No. 184,918, filed January 14, 1938 patented May 20, 1941 as Patent 2,242,432.

I have thus described generally my contribution to the art in order that the specific construc-

tion described hereinafter may be better understood, and that the relation of my contribution to the prior art may be better appreciated. I shall now describe the preferred specific form of my contribution to the art, it being understood, of course, that my contribution may be embodied in many specific forms by those skilled in the art without departing from the spirit and substance thereof.

In the drawings, Fig. 1 is an elevation of my truck, with certain parts shown in section to better illustrate their operation. Fig. 2 is a view similar to Fig. 1 with the parts in the same relation, showing the lifting platform of the truck located between the upper and lower floors of a reversible skid platform or pallet. Fig. 3 is a view similar to Fig. 2, showing the elevating platform in elevated position. Fig. 4 is a view looking downwardly on Fig. 1 with the operating parts of the truck platform exposed by the elimination of covering plates. Figs. 5 and 6 are respectively sections along lines 5—5 and 6—6 of Fig. 1. Fig. 7 is a perspective view of the front end of the elevating platform and the parts connecting that end of the platform to the lifting head, taken somewhat along the lines 5—5 of Fig. 1.

Referring now more particularly to the drawings, the lifting head of my truck is designated by reference numeral 10, and may be considered as practically identical with the lifting head of the truck shown in the Stuebing Patent No. 1,785,368. Since the construction of the lifting head of the platform of my truck is not in itself a part of my contribution to the art, I shall not in this specification venture into much detail in describing it, since those desiring to ascertain its construction may refer to the said Stuebing patent.

However, it may be well to indicate that the lifting head comprises supporting wheels 11, and a steering and lifting handle 12, downward swinging movement of which actuates a strut member 13, which in turn moves a lever 14 on which is mounted a lifting pawl 15 cooperating with a lifting ratchet 16. Integral with the lifting ratchet 16 are lifting links 17. A holding pawl 17 is adapted to hold the lifting ratchet 16 in any position to which it is rotated by the lifting pawl 15. A controlling cam 18 is manipulated by a foot treadle 20 to control the release of the lifting pawl 15 and the holding pawl 17 relatively to the lifting ratchet 16.

In one position of the treadle 20 shown in Fig. 1, both the lifting and holding pawls are in

contact with the lifting ratchet so that a series of downward swinging movements of the lifting handle 12 will rotate the ratchet 16 to rotate the lifting links 19 from their initial position of Figs. 1 and 2 to their position of Fig. 3. Movement of the treadle 20 will, through the cam 18, move both the lifting and holding pawls out of contact with the ratchet 16, and allow the lifting links 19 to move from their position of Fig. 3 to their position of Fig. 1 incidental to the lowering movement of the elevating platform. So far as my contribution is concerned, it is merely necessary to consider that the elevating platform is lifted as the lifting links 19 are rotated clockwise, and that when the links 19 are released for counterclockwise movement, the elevating platform will be moved to a lowered position, as will be described presently.

The elevating platform of my truck is U shaped, as best shown in Fig. 4, and comprises a pair of identical platform legs 21 and a saddle 22. It will of course be appreciated that for many purposes, a truck platform similar to that shown in the Stuebing patent supra may be utilized instead of the elevating platform which I prefer, and which is shown herein. The saddle 22 is constructed to hold together the platform legs 21, and the said saddle extends vertically, as best illustrated in Figs. 5 and 7, to a point 23. At each side of the saddle, somewhat below the portion 23 thereof, there are secured a pair of plates 24. Each pair of plates 24 supports a pivot shaft 25 on which is pivoted a link 26. The other end of each link 26 is pivoted at points 27 to the lifting head 10.

At each side of the lower end of the platform saddle, there is secured a plate 28 which supports one end of a shaft 29. Each of the shafts 29 extends from plate 28 through a side bar 30 of one of the platform legs, through plates 31 and 32 of the saddle, and then through the other side bar 33 of the particular platform leg. Mounted on each of the shafts 29 is a pair of lifting struts 34 which are secured by a pivot shaft 35 to each one of the lifting links 19 of the lifting head. It is therefore readily seen, especially from Figs. 1 and 7, that a clockwise rotation of the lifting links 19 will impart movement to the lifting struts 34 to lift the saddle 22 of the elevating platform through shafts 29.

Mounted on each of the shafts 29 between plates 31 and 32 of the saddle is a peculiarly shaped front end connecting link 36. Each front end connecting link comprises a lever 37 welded as at 38 to a sleeve 39 fitting about the shaft 29. Welded to the sleeve 39, or otherwise suitably secured thereto, are a pair of ears 40 which in turn are secured by a pivot shaft 41 to a rod 43 through a suitable clevis 44. In order to allow for ready adjustment of the rod 43, it may be in threaded relation to the clevis 44, as will be appreciated by those skilled in the art. Each lever 37 is secured at its front end through a pivot shaft 45 to the lifting head 10. It will now be appreciated that when the saddle 22 moves vertically from the position of Figs. 1 and 2 to the position of Fig. 3, the upper and lower connecting links 26 and 36 will swing from their positions of Figs. 1 and 2 to their position of Fig. 3, and that this will effect movement of the rods 43 to the right (looking at Figs. 1, 2 and 3). This movement of rods 43 is utilized for lifting the rear end of the elevating platform simultaneously with the front end thereof.

For this purpose, each of the lifting legs 21

has pivoted thereto at 46 a rear lifting link 47, each carrying wheels 48. Each of the rods 43 is, of course, secured in adjustable relation to a clevis 49 which is pivoted at 50 to each of the links 47 to impart movement thereto. As the rods 43 move to the right from the position of Figs. 1 and 2 to the position of Fig. 3, the links 47 are rotated counterclockwise, and the wheels 48 are moved into the positions shown in Fig. 3, thereby elevating the platform, as is self-evident.

As was indicated earlier in the specification, the truck of this invention is especially designed for use with reversible pallets of the type disclosed in my application supra, the rear wheels 48 being intended to enter between the boards 51 of a reversible pallet for lifting the pallet, all as is shown in Figs. 2 and 3. In order that the truck may enter between the upper and lower floors of such a platform, I equip the rear end of each of the platform legs of my truck with a series of rollers 52, whose positions are so graduated that first one of the rollers will contact the platform, then the second, and then the third, gradually lifting each of the platform legs into the space between the upper and lower floors. Moreover, the series of rollers 52 assist in facilitating the movement of the truck to its position of Fig. 2 relatively to the reversible pallet by co-operation with each of the successive lower floor boards 51.

Similarly, to assist in withdrawing the truck from between the upper and lower floors of a reversible pallet, I employ a further series of rollers 53, whose operation will be readily understood. Additional rollers 54 further assist in the movement of the platform legs 21 into and out of the pallet.

Incidentally, it will be well to indicate at this time that I utilize the spread platform legs 21 because the floors of the usual type of reversible skid pallet are separated by a longitudinal beam, not herein shown, the platform legs 21 being adapted to enter the pallet on each side of said longitudinal beam, all as is best set forth in my application supra.

As I have already explained, lifting movement of the elevating platform of my truck is imparted thereto by vertical movement thereof on the upper and lower links 26 and 36 relatively to the lifting head 10. Those skilled in the art will well appreciate that the upper and lower lifting links 26 and 36 act to maintain the platform in parallelogram relationship to the lifting head 10, whereby so long as the platform legs 21 comprising the lifting platform of the truck, are maintained parallel to the ground, the lifting head 10 will be maintained perpendicular to the ground, all as is desirable in this art. Where the floor is horizontal, the lifting head 10 will be maintained in a vertical plane, which is desirable for best operation thereof. The relationship of the rear lifting links 47 to the upper and lower lifting links 26 and 36 is, of course, preferably as has already been indicated, so that the rear end of the elevating platform will be lifted at substantially the same rate as the front end thereof.

Since, as has already been indicated, vertical movement of the elevating platform relatively to the lifting head 10 acts to move the wheels 48 carried by the rear lifting links 47, from the position of Fig. 2 toward the position of Fig. 3, it will be readily appreciated that when the extreme rear rollers 52 of the platform legs 21 first encounter a board 51 of the pallet, those rollers 52 will act to lift the pair of platform legs 21 and

therefore the entire platform including the saddle 22, relatively to the lifting head 10. This is particularly true when using mechanical lifting means of the type herein disclosed, and which are readily movable through the application of lifting pressure to the platform. If this relative movement were not resisted, it would cause the links 47 to rotate towards the position of Fig. 3, bringing the wheels 48 down below their position in Fig. 2, so that the said wheels would form a considerable obstruction against the movement of the platform legs 21 further into the space between the upper and lower floors of the reversible pallet. As a matter of fact, such movement of the wheels 48 would offset all of the benefits obtained by the utilization of the rollers 52, and also of the rollers 53 and 54.

I therefore provide springs 55 which are mounted about each of the rods 43 and press at one end against a plate 56 secured to the side bars 30 and 33 of each of the platform legs 21. At their other ends, the springs 55 press against an adjustable nut 57 on the rods 43. The springs 55 therefore function to prevent rotation of the links 47 from the position of Fig. 2 to the position of Fig. 3 when the elevating platform is lifted relatively to the lifting head 10 through the application of lifting pressure to the platform itself.

In this way, when the platform is lifted somewhat as in the position of Fig. 2, the wheels 48 will not move downwardly to obstruct the operation of the rollers 52, 53 and 54. Rather, the entire truck will pivot about the wheels 11 under the lifting head. Naturally, when the lifting mechanism itself is actuated and the lifting links 19 are rotated, moving the lifting struts 34, there will be a forceful separation between the lifting head 10 and the lifting platform, causing an upward movement of the platform and a corresponding downward movement of the wheels 48 at the rear ends of each of the platform legs 21.

In order to effect a smooth lowering of the lifting platform when the holding pawl 17 is released, I employ a liquid dashpot 58 of the type standard in this art. The plunger portion 58a of the dashpot 58 is secured at its upper end through suitable linkage mechanism to a pair of angle irons 59 welded to the upper end of the saddle 22 near the portion 23 thereof. The lower end of the dashpot 58 is pivoted through a shaft 60 to the lower end 61 of a bracket 62 which is secured as by welding at 63 to the rear plate of the lifting head 10. The dashpot 58 being mounted in the particular position shown, very readily follows the upward movement of the elevating platform and readily controls the downward lowering movement of the platform.

Having now described a preferred modification of my invention, I claim:

1. In a lift truck, a lifting head, wheels supporting said lifting head, an elevating platform, wheel supporting links pivoted to the rear end of said platform, supporting means securing the front end of said platform to the lifting head whereby to form an assembled truck, rods connecting said rear wheel supporting links to said supporting means, means on said lifting head for moving said platform upwardly relatively to said lifting head and through said supporting means and thereby to effect a movement of both said supporting means and said rear wheel supporting links whereby to lift simultaneously both ends of said platform, and springs for resisting movement of said platform relatively to said

head mounted about said rods, whereby application of lifting pressure to the said platform other than through said lifting head means will merely tilt said platform and lifting head as a unit about the wheels supporting said lifting head.

2. In a lift truck, a lifting head, wheels supporting said lifting head, an elevating platform, wheels under the rear end of said platform, a vertically extending saddle at the front end of said platform, upper and lower links each pivoted at one end to said saddle and at the other end to said lifting head whereby to maintain a parallelogram arrangement between said links, said platform and said lifting head, means for moving the platform upwardly relatively to said lifting head through said links, rods extending from at least certain of said links for moving vertically the wheels supporting the rear end of said platform whereby to lift simultaneously the front and rear ends of said platform, guide lugs on said platform through which said rods extend, springs mounted about said rods and pressing at one end against said lugs and at the other end against a stop on said rods, and said springs resisting said movement of said platform relatively to said head, whereby application of lifting pressure to the said platform other than through said lifting head means will merely tilt said platform and lifting head as a unit about the wheels supporting said lifting head.

3. In a lift truck, a lifting head, wheels supporting said lifting head, an elevating platform, wheel supporting links pivoted to the rear end of said platform, links secured at one end to the front end of said platform and at their other end to the lifting head whereby to form an assembled truck and with the front end of the elevating platform supported by said lifting head, rods connecting said rear wheel supporting links to said front end links, means on said lifting head for moving said platform upwardly relatively to said lifting head and through said front end links, and thereby to effect a pivotal movement of said front end links and said rear wheel supporting links whereby to lift simultaneously both ends of said platform, guide lugs on said elevating platform for guiding said rods, and springs mounted on said rods and pressing against said guide lugs for resisting movement of said platform relatively to said head on said links, whereby application of lifting pressure to the said platform other than through said lifting head means will merely tilt said platform and lifting head as a unit about the wheels supporting said lifting head.

4. In a lift truck, a lifting head, wheels supporting said lifting head, an elevating platform, wheel supporting links pivoted to the rear end of said platform, supporting means securing the front end of said platform to the lifting head whereby to form an assembled truck, rods connecting said rear wheel supporting links to said supporting means, guide lugs on said platform traversed by said rods, means on said lifting head for moving said platform upwardly relatively to said lifting head and through said supporting means, and thereby to effect movement of both said supporting means and said rear wheel supporting links whereby to lift simultaneously both ends of said platform, rollers at the rear end of said platform and rearwardly of said wheels whereby said rollers tend to lift said platform as said rollers encounter an obstruction, and springs mounted about said rods and pressing

against said guide lugs for resisting movement of said platform by said rollers relatively to said head, whereby application of lifting pressure to the said platform by said rollers will merely tilt said platform and lifting head as a unit about the wheels supporting said lifting head.

5. In a lift truck of the class described, a lifting head, an elevating platform having a vertical hollow standard juxtaposed to said lifting head and enclosing a portion of said lifting head, upper and lower parallel links pivoted at their front ends to the lifting head and at their rear ends to said standard, a dashpot vertically disposed within said standard and pivoted at its lower end to said lifting head and at its upper end to said standard, wheel supporting links pivoted to the rear of said elevating platform, means connecting said wheel supporting links to at least certain of said parallel links whereby movement of said parallel links as the front end of said platform is elevated relatively to said lifting head, effects the rotation of said links to lift the rear end of said platform, and means on said lifting head for so lifting said platform.

6. In a lift truck of the class described, a lifting head, an elevating platform having a vertical hollow standard juxtaposed to said lifting head, upper and lower parallel links pivoted at their front ends to the lifting head and at their rear ends to said standard, a dashpot vertically disposed within said standard and pivoted at its lower end to said lifting head and at its upper end to said standard, wheel supporting links pivoted to the rear of said elevating platform, means connecting said wheel supporting links to at least certain of said parallel links whereby movement of said parallel links as the front end of said platform is elevated relatively to said lift-

ing head, effects the rotation of said links to lift the rear end of said platform, and means on said lifting head for so lifting said platform.

7. In a lift truck of the class described, a lifting head, an elevating platform having a vertical hollow standard juxtaposed to said lifting head, upper and lower parallel links pivoted at their front ends to the lifting head and at their rear ends to said standard, a dashpot vertically disposed within said standard and pivoted at its lower end to said lifting head and at its upper end to said standard, wheel supporting links pivoted to the rear of said elevating platform, means connecting said wheel supporting links to at least certain of said parallel links whereby movement of said parallel links as the front end of said platform is elevated relatively to said lifting head, effects the rotation of said links to lift the rear end of said platform, and means extending between said lifting head and said lower parallel links for actuating said links to lift said platform.

8. In a lift truck of the class described, a lifting head, an elevating platform having a vertical standard juxtaposed to said lifting head, upper and lower parallel links pivoted at their front ends to the lifting head and at their rear ends to said standard, wheel supporting links pivoted to the rear of said elevating platform, means connecting said wheel supporting links to at least certain of said parallel links whereby movement of said parallel links as the front end of said platform is elevated relatively to said lifting head, effects the rotation of said links to lift the rear end of said platform, and means extending between said lifting head and said lower parallel links for actuating said links to lift said platform.

GEORGE QUAYLE.
